UNITED STATES PATENT OFFICE.

FRED SIGN, OF WESTBORO, WISCONSIN.

WEAPON.

1,252,853.

Specification of Letters Patent.

Patented Jan. 8, 1918.

Application filed April 13, 1917. Serial No. 161,757.

To all whom it may concern:

Be it known that I, FRED SIGN, a subject of the Emperor of Austria, resident of Westboro, county of Taylor, and State of Wisconsin, have invented certain new and useful Improvements in Weapons, of which the following is a specification.

This invention relates to improvements in weapons for defense, and offense, and has 10 as its principal object the provision of means whereby a pistol may be converted so as to be used as a sword.

A further object is to provide such devices in forms which may be readily secured 15 to an ordinary pistol so that either weapon may be used without conflicting with the other.

These and other like objects are attained by the novel design, construction and combination of parts hereafter described and shown in the accompanying drawing, forming a material part of this specification, and in which:—

Figure 1 is a side elevational view of an 25 implement made in accordance with the invention.

Fig. 2 is a partial side elevational view of the sword hilt as applied to the pistol, and

Fig. 3 is a transverse sectional view taken 30 on line 3—3 of Fig. 1.

The drawings represent a relatively thin pistol of the repeating type in which the cartridges are contained within the hilt or handle 10, the same being projected up by a spring in the ordinary manner to the upper or barrel portion 11 and fired by the lock mechanism 12, the pistol being representative of ordinary well-known types as 40 now constructed.

Attached to one side of the pistol is a sword hilt 14 adapted to be grasped by the hand, the fingers of which pass into the opening 15 and are protected by the guard 16 so that a secure grip may be attained, the hand being measurably protected by the 15 guard.

Extending outwardly and in front of the hilt, which is secured by means of screws or rivets 17 to the pistol side is a blade 18, such as a rapier, saber or sword, and which is so firmly held in connection with the side of the pistol that the two are used as one and without conflicting, the blade in no wise interfering with the discharge of the 50 pistol, and the pistol not interfering with 55 the use of the blade when in close proximity with an adversary.

From the foregoing, it will be readily seen that a weapon of the class described 60 has been disclosed which is capable of being used in warfare or otherwise, in an efficient manner.

Having thus described my invention, what I claim as new, and desire to secure by 65 Letters Patent, is:—

The combination with a pistol having a relatively flat sided barrel, of a blade having a hilt rigidly secured alongside said barrel, an extension formed with said hilt, 70 said extension being disposed at a right angle to said blade and having an opening receptive of the operator's hand, and a guard formed so as to inclose the opening.

In testimony whereof I have affixed my 75 signature.

FRED SIGN.
